UNITED STATES PATENT OFFICE

LESTER U. LARKIN, OF ATLANTA, GEORGIA

REFRIGERATION METHOD AND APPARATUS

Application filed June 28, 1928. Serial No. 288,824.

This application is a combination in part of my copending application Serial No. 243,848 filed December 31, 1927.

This invention relates to refrigeration in general and particularly to cooling units adapted for use in display case refrigerators, refrigerator cars, storage rooms, household refrigerators, etc.

In cooling units, heretofore commonly used, it has been customary to solder tinned copper heat absorbing plates to tinned copper cooling tubes extending lengthwise and in contact with the sides of plates; which is obviously an expensive and time consuming method. Moreover the solder interposes a contact medium between the absorbing plates and the cooling tubes which is of less heat conductivity than the plates and tubes; and therefore retards, to some extent, the flow of heat from the absorbing plates into the cooling liquid in the tubes.

In the most efficient units heretofore used, the ratio of cooling surface of the absorbing plates to the radiating outer surface of refrigerators has been largely a matter of guess-work; and, generally has been such as to require a large difference between the temperature of the cooling units and the temperature maintained at the center of the refrigerator casing. In refrigerators for preserving meats and the like, the result arising from this great temperature difference is very inefficient; meats lose a great deal of weight by dehydration due to exposure to below freezing temperature, and due also to the high rate of air circulation caused by this great temperature difference.

Exhaustive tests, conducted with the most efficient and widely marketed cooling units heretofore used and having their heat absorbing plates soldered flat against the cooling tubes, have been made. These tests, made with an 8' x 6' x 10' well insulated cooler, show that in order to maintain a temperature of 36 degrees F., one half way up in the cooling compartment, it is necessary to maintain a temperature of not less than 21 degrees on the absorbing plates. This results in heavy frosting of the absorbing plates with consequent reduction in efficiency and dehydration

of the meats, etc., exposed to rapidly circulating air at very low temperature.

As the desired temperatures to be maintained decreases, the temperature differences, with prior coils, increase. For example, in a 12 foot display case with the most widely used coils at the ends thereof, it has been found that in order to secure a temperature of 32 degrees at the center of the case, it is necessary to reduce the temperature of the end coils to at least 8 degrees, with the concomitant quick and heavy frosting and reduction in efficiency.

The main object of the present invention is to provide a cooling unit capable of being manufactured at a much lower cost than any unit of corresponding cooling power heretofore known and used, and which, in its use, eliminates all the undesirable effects resulting from use of prior cooling units. The decrease in cost of manufacture of the present cooling unit results from the substitution of aluminum heat absorbing plates for the copper plates heretofore used.

Contrary to general understanding, actual tests demonstrate that aluminum has a greater rate of heat conductivity and absorption than copper. Long bars of copper and aluminum, identical in all dimensions and having one end of each exposed to the same temperature for a given time show that the other end of the copper rises in temperature nearly twice as fast as the corresponding end of the aluminum bar. Tests of this nature have given rise to the commonly accepted idea that copper has nearly twice the heat conductivity of aluminum. This result is due, however, to the fact that the aluminum radiates heat much faster than copper. Using comparatively short identical shaped bars of each metal, actual tests demonstrate that the temperature of aluminum rises more rapidly than copper exposed to the same degree of heat; it is also found that it loses its temperature more rapidly than copper.

This property of aluminum involving rapid absorption and radiation of heat is taken advantage of in the present invention, wherein aluminum heat absorbing plates are substituted for the copper plates heretofore used.

One great difficulty, however, arises in using aluminum plates as heat absorbers on copper tubes. Aluminum cannot be soldered to any metal by any cheap flowing solder; and the joints formed by any solder known at present will not stand up and are altogether very unsatisfactory. Moreover, the solder forming this joint acts as a heat insulator and thereby decreases the efficiency of the cooling unit.

In order to avoid the expensive and unsatisfactory job of soldering aluminum heat absorbing plates to the cooling tubes, the aluminum plates are mounted perpendicularly to the cooling tubes, and are forced or shrunk thereon, without soldering, to form a very tight joint between the plates and tubes. In forming the joint, say for an aluminum plate of No. 24 U. S. S. gage on a $5/8$ inch tube of aluminum, copper, or other metal, it is preferable to draw the plate at the center point of the joint; then punch a one-eighth inch hole clean through the center of the depression formed by the drawing. Next, the metal around the punched hole is drawn and expanded until a cylindrical flange of about $1/8$ inch in diameter and one-half inch deep projects from the face of the aluminum plate. The plate is then forced over the tube to the position desired, and is held in such position by the friction between the cylindrical flange and the tube.

The aluminum plates may be heated before being applied to the tubes in order to expand them and their joint openings to facilitate application of the plates to the tubes. When the plates, mounted hot on the tubes cool, they shrink on to the tubes and the joint becomes extremely tight and heat conductive.

Theoretically it would seem preferable to use aluminum tubes as well as aluminum plates; but, the difficulty of soldering aluminum to aluminum or any other metal, practically prohibits such construction. The tubes must have their ends connected to a float tank regulating the supply of cooling liquid to the tubes of the unit. These tanks and the tubes connected thereto are usually made of copper, and tinned copper tubing is not only very readily soldered to the copper tank, but the soldering thereof costs a great deal less and makes a much stronger joint than would be possible if aluminum tubes were substituted for copper tubes.

While untinned copper may be used, the tinned copper tubing is so cheap that it is more economical to use it throughout, than it would be to use plain copper tubing and tin the soldered joints where such joints must be made. Moreover, since tin has the same coefficient of expansion as aluminum, its use as a coating for copper tubing aids in maintaining the close friction joint between the absorbing plate and the tubes.

For the best results in using cooling units

of the type disclosed herein, it has been found by actual test that the total surface area of the heat absorbing plates should be equal to the outside radiating surface of the chamber to be cooled and that the cooling tubes passing perpendicularly through these plates should be spaced not more than $3\frac{1}{2}$ inches between centers, and the edges of each plate should be not more than $1\frac{3}{4}$ inches from the nearest cooling tubes.

There is an outer margin of $1\frac{3}{4}$ inches between the outer edges of each plate and the nearest tubes, and the plates are bored to fill the space enclosed by this margin with pipes spaced not more than $3\frac{1}{2}$ inches apart.

This results in the formation of a point at which the rate of radiation approximately equals the rate of heat conductivity for the type of evaporator described in my application.

Preferably the tubes are $5/8$ inches in diameter and of .625 inch tinned copper; and the aluminum plates or fins preferably No. 24 U. S. S. gage.

With units constructed as described and in the proportions described, with regard to the chamber intended to be cooled, it has been found by actual test that a temperature of 36 degrees F. can be maintained in the center of a $8' \times 6' \times 10'$ cooler by maintaining the coil with the temperature on the absorbing fins at between 34 and 35 degrees. The temperature difference in this case is less than two degrees. The most efficient of the prior coils now in common use requires a temperature difference of not less than fifteen degrees to maintain the center of the same cooling at 36 degrees F.; that is the temperature on the cooling fins that must be held at not higher than 21 degrees.

It is of course to be understood that the present cooling unit must be arranged in the hottest part of the casing to be cooled and that the tubes must extend in a direction perpendicular to the direction of circulation of the air to be cooled in said casing, with the fins parallel to said direction.

With the present type coil properly arranged in the casing, a temperature of 36 degrees F. can be maintained in the casing without frosting the plates at all, and consequently without freezing or dehydrating any of the contents of the casing whatever. The very large surface area and rapid heat absorption of the aluminum plates all lead to a rapid temperature drop when the unit is in operation. Since this temperature drop is less than two degrees, it follows that each refrigerating cycle of operation must be of very short duration, and consequently, must greatly reduce the amount of power required to maintain it in operation.

Whatever little moisture may be picked up from the air in the casing is deposited on the plates; and, because of the large surface

area of these plates, must, when condensed, be spread on such plates in a very thin film, which is constantly being removed by the circulating air and returned to the air and 5 meats from which it was taken.

Where below freezing temperature must be maintained on the plates, as in prior coolers, it is obvious that any moisture taken from the meats become condensed and frozen on 10 the plates and cannot be removed therefrom by the circulating air. In this case, the meats not only lose weight, which cannot be recovered, but also deteriorate greatly in quality.

15 This maintenance of humidity is only one of the most important results flowing from the use of cooling coils designed as disclosed herein. The short duration of refrigerating cycles cuts the cost of maintaining a stand- 20 ard cooling temperature by about fifty per cent as compared with the coils most widely sold heretofore. This has been proved by actual comparative tests by using the same refrigerator casing with identical operating 25 mechanism under identical conditions, but with the present coil substituted for the older coils.

Other objects and advantages of the invention will become apparent as the detailed description of several specific embodiments 30 thereof proceeds.

Fig. 12 is a view taken at right angles to the view shown in Fig. 11.

Referring to the drawings:

Fig. 1 shows a refrigerator casing 1, of the 60 show case type, having improved cooling units 2 and 3 suitably supported at opposite ends of the casing 1.

Each unit shown in Fig. 1 is illustrated in detail to a larger scale in Figs. 2, 3, 4, and 65 5. As shown in said figures each unit com-

prises what is commonly known in this art, as a "boiler" 4. One end of boiler 4 is provided with a valve 5 to control the admission of cooling liquid from a condenser, or other suitable source of supply, into the boiler 4; and is also provided with a valve 6 to control the egress of vapor derived from the cooling liquid previously admitted to said boiler, to a suitable compressor and other apparatus designed to recondense the vapor to a liquid. 70

The boiler 4 is old; and valves 5 and 6, and all the other mechanism, to control the ingress of condensed cooling liquid and the egress of vaporized cooling liquid to and from the boiler 4, are also old and well known 80 in this art; and for this reason are not shown nor described in detail herein. The boiler 4 and valve mechanism carried thereby, however, do form a new combination with the cooling tubes and heat absorbing fins arranged to form the new refrigerating unit; and, the unit as a whole, arranged in the refrigerator casing in the particular manner disclosed and claimed herein, forms with said casing a combination producing new and useful results long sought for by persons skilled 85 in this art.

As shown in Figs. 2 to 5, inclusive, of the drawings, the boiler 4 is intended to be arranged substantially horizontally with the 90 liquid control valve 5 in the lowest position. The cooling liquid is conducted from the lower part of boiler 4 through tubes 7, 8, 9 and 10, to the lower end of a group 11 of heat absorbing plates 12 arranged vertically 95 and parallel to each other.

As shown particularly in Figs. 2 and 4, the ends of these tubes are connected, respectively, to one end of U-shaped tubes 13, 14, 15 and 16, preferably by soldered joints commonly used to connect tubes together. 100

Vertically arranged above the tube 13 are the similar U-shaped tubes 17 and 18, having their branches 19, 20, 21 and 22 parallel to the branches 23 and 24 of the tube 13. The branch 23 is connected to branch 22 by a bend 25; branch 21 is connected to branch 20 by bend 26; and, finally branch 19 is connected to the boiler 4 by a bend 27. 110

The construction just described obviously, arises from manufacturing necessity. While a single tube, such as tube 7, might be coiled in and out of the plates 12, it is clearly much easier to make the U-shaped branches separately and connect their free ends to form a 120 closed conducting circuit from and to the boiler 4. The tube 7 is connected to the lowest branch 24 and the bend 27 connects the top branch 19 to the boiler at a point higher than the connection between boiler 4 and tube 7. This is to avoid heating of the cooling liquid by the plates 12 until the liquid in tubes 7 has reached its lowest point, and thereby aid in the circulation of the cooling liquid through the coils. 125

Obviously, if the plates 12 were applied to tube 7 at or immediately below the boiler, the absorbed heat would at once tend to vaporize the cooling liquid and would slow down the circulation through the whole circuit. By leaving tube 7 free of heat absorbing plates, the cold liquid falls rapidly by gravity to branch 24 and the plates 12 acting on this liquid tends to vaporize it and effect its return to the boiler 4.

Vertically above the U-shaped tubes 14, and extending similarly through the plates 12 are the similar U-shaped tubes 28 and 29 connected by bends 30, 31 and 32 to conduct the cooling liquid through the group of plates 12 to the boiler 4 at a point somewhat higher than the point at which the tube 33 conducts liquid from the boiler to the lower branch of U-shaped tube 14.

The arrangement of U-shaped tubes and bends above tubes 15 and 16 is identical with the arrangement of the corresponding tubes above tubes 13 and 14, and the parts are symmetrically arranged on opposite sides of a vertical plane, passing between the tubes 8 and 9, and perpendicular to the plates 12. This matter needs no further description, as the arrangement and operation will be obvious from inspection of the drawing. The main point to observe in connection with this embodiment, is that the tubes conducting cooling liquid from the boiler 4 do not contact with the heat absorbing plates 12 until they arrive at their lowest point remote from the boiler.

A modified form of unit is illustrated in Figs. 6, 7, 8 and 9. In this form the boiler 34 has its axis parallel to the heat absorbing plates 12' and perpendicular to the tubing passed through said plates.

The cylindrical side of boiler 34, remote from the group of plates 12' is provided with a valve 35 to control the egress of vaporized cooling liquid from boiler 34, and with a valve 36 controlling the supply of cooling liquid to said boiler. These valves and the float mechanism controlling the level of the liquid in the boiler, are old, and the specific details thereof constitute no part of the present invention. The novelty in this, as in the previously described form, resides in connecting the pipes conducting the cooling liquid from the boiler 34 directly to the bottom or colder part of the boiler and in connecting the vapor return pipes to the boiler at higher parts thereof.

As in the previously described embodiment, the pipes conducting the cooling liquid from the boiler to the group of cooling plates are not connected to said plates until they have reached their lowest point remote from the boiler. These constructions eliminate the possibility of heat derived from the plates 12 or 12' from retarding the flow of cooling liquid from the tanks, and permits the liquid

to fall by gravity, and in its coldest state, until it enters the group of heat absorbing plates at the lowest point.

In the second embodiment of the invention a bank of eighteen pipes are connected to the bottom of the boiler 34, which is normally vertical; and, at various distances from said bottom, these pipes are bent to form horizontal branches extending through the group 11' of heat absorbing plates 12'. A second bank of eighteen pipes are passed perpendicularly through the upper half of said group 11' and are connected to the cylindrical side of said boiler to return vaporized cooling liquid to the boiler. The second bank of pipes are connected to the first by vertically arranged U-shaped bends soldered to the ends of each bank. As these outflow and return pipes are symmetrically arranged on opposite sides, a plane bisecting plates 12' and boiler 34, only one vertical tier of pipes need be described herein, as the tiers are similar and are similarly arranged.

In Fig. 5, the first vertical tier of pipes comprises the three outlet pipes 37, 38 and 39 connected to the bottom of boiler 34 and these pipes are bent to form horizontal branches 40, 41 and 42, respectively, which pass perpendicularly through the lower half of the group 11' of plates 12'. Vertically arranged above these branches 40, 41 and 42 are the return branches 43, 44 and 45, passed through the upper half of group 11' of plate 12' and bent to connect with the cylindrical side of boiler 34.

The lowest outlet branch 40 is connected to the lowest return branch 43 by a U-shaped bend 46; and similar bends 47 and 48 connect the ends of branches 41 and 40 to the return branches 44 and 45, respectively. The branches are spaced apart vertically and equidistantly so that the U-shaped bends connecting them may be made all of the same standard size.

As shown clearly in Fig. 9, the center bend extends straight between the branches 40 and 44, while the bends 46 and 48 are curved to provide for proper connection, around branches 40 and 44, to the branches 42, 43 and 40, and 45. This formation of the bends permits the branches to be passed in vertical tiers through the plates 12' and avoids the necessity for staggering said branches, through the plates 12'.

The plates 12 and 12' are preferably formed of aluminum, and the tubes are made of tinned copper. Copper is preferred for the tubing because of its non-corrosive properties; and because it can be very easily soldered to the boilers and to the bends connecting the ends of one branch to another.

The aluminum plates cost about one third of the price of copper plates of the same dimensions; are more easily cut, punched and drawn, than copper plates; are much

lighter; and, actual tests, show the aluminum radiates and absorbs heat more rapidly than copper.

While the prior art in a somewhat related field, shows that heat absorbing fins have been arranged perpendicularly across a group of pipes as shown in this case, the prior art does not show that aluminum plates or fins have been used for this purpose. Heretofore, all such fins have been brazed or soldered to the pipes; and, heretofore, aluminum could not be soldered to the pipes. At the present time, aluminum solder is too expensive for commercial use, and it is too unreliable even when it is used.

In the particular field in which the present invention is employed aluminum plates have never been used for heat absorbing purposes, because prior heat absorbing plates, where used, were invariably soldered to the sides of the tubing, and because the cost of soldering such plates, if made of aluminum, would be wholly prohibitive, and the joints poor. Moreover, these aluminum plates had never been used previously, because it was the general impression in the art that aluminum was a poorer conductor of heat than the copper commonly used.

By actual test it has been discovered that aluminum plates absorb and radiate heat more rapidly than copper and this is the main reason for the selection of aluminum in the present invention. The difficulty of connecting aluminum to copper is overcome by the following method.

Each of the aluminum plates 12 or 12' is first slightly drawn at the points where the tubes are to pass through and a hole of about one eighth inch in diameter is punched 40 through the center of each depression formed by the first drawing operation. The drawn parts are then further drawn and each hole is enlarged to about nine-sixteenths inch and a flange 49 about one-half inch deep 45 is formed to project from one face of the plate.

In this case the plates 12 are intended to be forced on tubing five-eighths inch in diameter. The flanged plates may be preheated 50 to cause their flanged apertures to expand, and in this heated condition may be slid on to the tubing and allowed to cool. The cooling causes the aluminum plates to shrink and engage the copper tubes with enormous pressure.

55 sure which practically insures a perfect heat conducting joint between the plates and tubing. The tinned copper tubing and aluminum have substantially the same co-efficient of expansion, so that the joints once formed 60 as described, remain effective throughout the ranges of temperature to which the cooling units may be exposed.

The cooling units of this invention must be arranged with their fins vertical and parallel to the direction of air circulation in the

casing or chamber where they are installed. This is illustrated clearly in Fig. 1 where the units 2 and 3 are shown as mounted with their cooling tubes horizontal and with the absorbing fins parallel to the long axis of the case 1.

70 The form of cooler unit shown in Fig. 1 is to be preferred where the units must be arranged across a comparatively narrow casing, and access may be had to the boiler 4 from the top of the casing. The other form is 75 adapted to be used where a long narrow unit is necessary, as in counter cases having air circulating from front to rear instead of from end to end.

80 There is a decidedly new result obtained by positioning units of this type in the manner described in refrigerator casings. The very large cooling area of the heat absorbing fins absorbs heat very rapidly and consequently greatly decreases the duration of refrigeration cycles necessary to maintain a given temperature.

85 Where the casings are properly insulated, with five-eighths inch copper tubing spaced apart at 3½ inch between centers through aluminum fins having a surface area equal to the outside surface area of the casing, a temperature of 36 degrees F. can be maintained at the center of the casing by maintaining a 90 temperature of 34 degrees F. on the fins of the cooling units. Since this is above freezing point, this temperature of 36 degrees can be maintained without frosting the fins. It is obvious, too, that any moisture condensed on the fins will be removed, practically as 95 fast as formed, by the air circulating through the units; since this moisture must, because of the large condensing area of the fin, be formed in exceedingly thin films which can be readily absorbed by the circulating air.

100 The rapid rate of reduction in temperature by the units, and the small difference in the temperature between the temperature to be maintained in the casing and that on the cooling fins, obviously greatly reduces both the 105 time and cost of operation in comparison with the known cooling units involving a temperature difference of not less than fifteen degrees.

The elimination of soldered joints and braces between absorbing plates and tubes 110 also greatly decreases the cost of manufacture, in comparison with prior devices requiring the soldering of the plates to the sides of the tubes.

115 Having described the advantages involved in the manufacture and use of the present invention, and having fully disclosed the method of manufacturing it, what I now claim and desire to secure by Letters Patent is:

120 1. In a refrigerator, the combination with a chamber designed for the circulation of air in a given direction therein, of piping in said chamber having branches thereof extending in a direction substantially perpendicular to the direction of the circulating air, heat-ab-

125
130

sorbing fins secured perpendicularly to said branches and in heat-absorbing contact therewith and means for circulating a cooling fluid through said piping.

5. 2. In a refrigerator, the combination with a chamber designed for the circulation of air therein in a given direction, of a boiler mounted in said chamber and having valve mechanism controlling the ingress of cooling liquid thereto and the egress of vaporized cooling liquid therefrom, piping extending from said boiler to form a circulation path for said cooling liquid, heat absorbing fins connected perpendicularly to said piping and arranged in said chamber parallel to the direction of air circulation in said chamber.

10. 3. In a refrigerator, the combination with a chamber designed for the circulation of air in a given direction therein, a bank of heat-absorbing plates arranged in said chamber parallel to the said direction, piping passing perpendicularly through said plates and in heat-absorbing contact therewith, and means for circulating a cooling fluid through said piping.

15. 4. In a refrigerator, the combination with a chamber designed for the circulation of air in a given direction therein, a bank of heat-absorbing plates mounted in said chamber parallel to the said direction, a valve controlled tank for cooling liquid, piping connected to the lower part of said tank to conduct cooling fluid to the lower part of said bank of plates, and means to return said cooling fluid from said piping perpendicularly through said bank of plates to said tank.

20. 5. In a refrigerator, the combination with a casing having heat insulated walls, of a cooling unit mounted in said casing and comprising piping having a cooling liquid circulating therein, a bank of heat-absorbing plates connected to said piping and having a cooling contact area for the air in said casing equal to the area of the outside of said casing.

25. 6. In a refrigerator, the combination with a heat insulated casing of a tank mounted therein and having valves controlling the admission of cooling liquid to said tank and the release of vaporized cooling liquid therefrom, a bank of heat absorbing plates mounted below said tank parallel to each other and substantially vertical in said casing, a pipe connected to the lower part of said tank and extending to the lower part of said bank of plates, and piping connected to said tank and to the lowest end of said pipe, and having parts thereof extending perpendicularly through said bank of plates.

30. 7. In a refrigerator, a refrigerating unit comprising piping for a refrigerant having substantially parallel branches, and substantially parallel spaced heat absorbing fins secured substantially perpendicularly to said branches, said unit being arranged

35. with the fins approximately vertical, and means forming a chamber enclosing said unit, the walls of said chamber being positioned to determine a circulation of the air in said chamber induced by the convection flow of air between said fins.

40. 8. In a refrigerator, a refrigerating unit comprising a boiler having valve mechanism controlling the ingress and egress of refrigerant therefrom, piping extending substantially horizontally from said boiler to form a circulation path for said refrigerant, heat absorbing fins connected substantially perpendicularly to said piping, and means forming a chamber enclosing said unit, the walls of said chamber being positioned to determine a circulation of the air in said chamber induced by the convection flow of air between said fins.

45. 9. In a refrigerator, a refrigerating unit comprising a bank of spaced heat absorbing plates arranged approximately vertical, piping passing substantially perpendicular through said plates and in heat absorbing contact therewith, means for circulating a refrigerant through said piping, and means forming a chamber enclosing said unit, the walls of said chamber being positioned to determine a circulation of the air in said chamber induced by the convection flow of air between said plates.

50. 10. In a refrigerator, a refrigerating unit comprising a bank of spaced heat absorbing plates mounted substantially vertical, a valve controlled tank for a refrigerant, piping connected to the lower part of said tank to conduct a refrigerant to the lower part of said bank of plates, means to return said refrigerant from said piping perpendicularly through said bank of plates to said tank, and means forming a chamber enclosing said unit, the walls of said chamber being positioned to determine a circulation of the air in said chamber induced by the convection flow of air between said plates.

55. 11. In a refrigerator, a refrigerating unit comprising piping for circulating a refrigerant horizontally arranged, a bank of heat absorbing plates arranged approximately vertically and connected to said piping, and means forming a chamber enclosing said unit, the walls of said chamber being heat insulated, said walls being positioned to determine a circulation of the air in said chamber induced by the convection flow of air between said plates, the aggregate area of said plates being approximately equal to the area of the walls of said chamber.

60. 12. In a refrigerator, walls enclosing a refrigerating chamber, and a refrigerating unit therein having heat exchanging fins, said fins having an aggregate area substantially equal to the aggregate area of the bounding surfaces of the refrigerating cham-

ber, so as to produce efficient refrigeration within said chamber at a temperature differential between said unit and the atmosphere in said chamber so small as to avoid frosting of said refrigerating unit.

13. In a refrigerator, walls enclosing a refrigerating chamber, and a refrigerating unit therein, said unit including heat exchanging aluminum fins having an aggregate area substantially equal to the aggregate area of the bounding surfaces of the refrigerating chamber, so as to produce efficient refrigeration within said chamber at a temperature differential between said unit and the atmosphere within said chamber so small as to avoid frosting of said refrigerating unit.

14. In a refrigerator, walls enclosing a refrigerating chamber, and a refrigerating unit therein including substantially horizontal pipe sections and a plurality of fins in heat exchanging relation to said pipe sections and perpendicular thereto, said fins having an aggregate area so definitely related to the aggregate area of said walls as to produce efficient refrigeration within said chamber at a temperature differential between said unit and the atmosphere within said chamber so small as to avoid frosting of said refrigerating unit.

15. In a refrigerator, walls enclosing a refrigerating chamber, and a refrigerating unit therein including substantially horizontal pipe sections and a plurality of aluminum fins perpendicular to said pipe sections and in heat exchanging relation thereto, said fins having an aggregate area so definitely related to the aggregate area of said walls as to produce efficient refrigeration within said chamber at a temperature differential between said unit and the atmosphere within said chamber so small as to avoid frosting of said refrigerating unit.

16. In a refrigerator, walls enclosing a refrigerating chamber, and a refrigerating unit therein, including a plurality of substantially horizontal pipe sections and a plurality of aluminum fins arranged perpendicularly to said pipe section and in heat exchanging relation thereto, the aggregate area of said fins being substantially equal to the aggregate area of said walls so as to produce efficient refrigeration within said chamber at a temperature differential between said unit and the atmosphere within said chamber so small as to avoid frosting of said refrigerating unit.

17. In a refrigerator, walls enclosing a refrigerating chamber, and a refrigerating unit therein comprising an evaporator coil having a plurality of substantially horizontal pipe sections and a plurality of aluminum fins, each fin being common to said pipe sections and arranged perpendicularly thereto in heat exchanging relation therewith, said fins hav-

ing an aggregate area so definitely related to the aggregate area of said walls as to produce efficient refrigeration in said chamber at a temperature differential between said unit and the atmosphere within said chamber so small as to avoid frosting of said refrigerating unit.

18. In a refrigerator, walls enclosing a refrigerating chamber, and a refrigerating unit therein comprising an evaporator coil including a plurality of substantially horizontal pipe sections, a plurality of aluminum fins each fin being common to said pipe sections and arranged perpendicularly thereto and in heat exchanging relation therewith, said pipe sections being spaced in said fins so as to occupy the centers of the contiguous areas at whose bounds the rate of radiation approximately equals the rate of heat conductivity.

19. In a refrigerator, walls enclosing a refrigerating chamber, and a refrigerating unit therein comprising an evaporator coil including a plurality of substantially parallel pipe sections, a plurality of aluminum fins, each fin being common to said pipe sections, said pipe sections being spaced in said fins so as to occupy the centers of contiguous areas at whose bounds the rate of radiation approximately equals the rate of heat conductivity.

20. In a refrigerator, walls enclosing a refrigerating chamber, and a refrigerating unit having substantially horizontally disposed pipes, and substantially vertically disposed heat exchanging fins perpendicular to said pipes, said fins having an aggregate area so definitely related to the aggregate area of the bounding surfaces of said refrigerating chamber, that efficient refrigeration temperature is maintained in said chamber by the maintenance of a fin temperature not materially lower than 32 degrees F. whereby frost does not form on said refrigerating unit.

21. In a refrigerator, a refrigerating unit comprising a continuous pipe conduit for refrigerant having a plurality of substantially parallel portions arranged in a plurality of superposed substantially horizontal banks, with a plurality of said portions in each bank, heat absorbing fins disposed perpendicularly to said portions and in heat absorbing contact therewith, the elements of said unit being so dimensioned as to determine a focal region in said refrigerator for originating and maintaining a definite convection circulation of air within said refrigerator.

22. In a refrigerator, a refrigerating unit comprising a continuous pipe conduit for refrigerant having a plurality of substantially parallel portions arranged in a plurality of superposed substantially horizontal banks, with a plurality of said portions in each bank, heat absorbing fins each com-

- mon to all said portions disposed perpendicularly to said portions and in heat absorbing contact therewith, the elements of said unit being so dimensioned as to determine a focal region in said refrigerator for originating and maintaining a definite convection circulation of air within said refrigerator.
23. In combination with an evaporating tank, a pipe loop connected at its ends to said tank and having parallel limbs extending substantially horizontally, and a sheet metal heat absorbing fin extending perpendicularly to, and in heat absorbing contact with each of said pipe limbs.
24. In combination with an evaporating tank, a pipe loop connected at its ends to said tank and having parallel limbs extending substantially horizontally, and thin sheet metal heat absorbing fins extending perpendicularly to said limbs and in heat absorbing contact with at least one of said limbs.
25. The combination with an evaporator tank having mechanism to control the admission of condensed cooling fluid thereto and the suction of vaporized cooling fluid therefrom, a pipe connected to and extending substantially horizontally from said tank to conduct cooling fluid therefrom, a second pipe connected to said tank and extending parallel to the first named pipe to return to said tank the fluid passed through the first named pipe, a heat absorbing fin extending perpendicularly to and in heat absorbing contact with each of said pipes, and means for conducting said fluid from the end of the first named pipe remote from said tank to the corresponding end of the other tank.
26. The combination with an evaporator tank having mechanism to control the admission of condensed cooling fluid thereto and the suction of vaporized cooling fluid therefrom, of a heat absorbing fin, pipes connected to said tank and extending substantially horizontally and parallel to each other perpendicularly through said fin and in heat absorbing contact therewith, and means for conducting cooling fluid from some of said pipes to others to return the cooling fluid through said other pipes from the first named pipes.
27. In a refrigerating plant, a valve controlled evaporating tank, piping having its opposite ends connected to said tank and having parts thereof substantially horizontal and parallel to each other, and heat absorbing fins spaced along said parts perpendicularly thereto and in heat conducting contact therewith.
28. In a refrigerating plant, an evaporator comprising a valve controlled tank for cooling fluid, heat absorbing fins parallel to each other, pipes connected to said tank and extending substantially horizontally and parallel to each other perpendicularly

through and in heat absorbing contact with said fins, and means connecting the ends of said pipes remote from said tank to conduct cooling fluid from some of said pipes to others.

29. A container for cooling liquid, copper pipes having one end of each soldered to and extending from the container to conduct said liquid from and return it to said container, said pipes having horizontally disposed parts thereof parallel to each other, aluminum fins extending perpendicularly to all of said parts and held by friction in heat conducting contact therewith, and means soldered to the other ends of said pipes to provide passage for said liquid between the said conducting and return pipes.

30. A cooling unit comprising a valve controlled evaporator float tank for cooling liquid, a group of pipes connected to said tank to conduct cooling liquid therefrom, a second group of pipes connected to said tank to return the liquid to said tank after passage through the first named group, means connecting the free ends of said group to conduct liquid from the first named group to the second, all of said pipes being parallel to each other and substantially horizontally disposed, and heat absorbing fins secured perpendicularly to each of said pipes and in heat conducting contact therewith.

31. A combination with an evaporator tank having mechanism to control the admission of cooling liquid thereto and the suction of vaporized cooling liquid therefrom, heat absorbing vertical fins parallel to each other, tubes extending vertically from the lower part of said fins to conduct cooling fluid by gravity therefrom and having parts bent parallel to each other and passing perpendicularly through and in heat conducting contact with said fins, tubes connected to a higher part of said tank than the first named tubes to return vaporized cooling fluid to said tank and also having parts parallel to each other and passing perpendicularly through and in heat absorbing contact with said fins above the parallel parts of the first named tube, means for conducting cooling liquid from the first to the second named tubes, the parts of said conducting tubes entering said fins at their points remote from said tank.

In testimony whereof I affix my signature.
LESTER U. LARKIN.
